UNITED STATES PATENT OFFICE.

BARNEY BILLET AND SAMUEL HEILWEIL, OF NEW YORK, N. Y.; SAID HEILWEIL AS-
SIGNOR TO SAID BILLET.

SKULL-SHAPING MEANS.

Application filed April 20, 1926. Serial No. 103,225.

Our present invention relates to the treatment of animal skins, and has particular reference to a method of shaping and treating the skins in the manufacture of scarfs.

- 5 It is an object of the invention to provide a method for shaping animal skins to stimulate animals' heads, and coordinately our invention involves the apparatus with which we accomplish this result.
- 10 Where we have attempted to shape an animal skin in the manner specified by wetting the skin and stretching it upon a wooden mold, we have found it necessary to leave the skin upon the molds for periods as long
- 15 as two days, so that the wooden mold might dry. It is an object of the present invention to provide an apparatus which will permit the shaping of the skins in a much more efficient, economical, and quicker manner, with
- 20 the result that great savings are effected both in labor and in time.

A feature of the invention lies in providing a mold similar to the wooden mold referred to, but having a surface which is non-absorptive; and in a preferred embodiment the mold is constructed of metal.

Another feature of the invention lies in associating with the mold means for electrically heating the mold at predetermined intervals so that the drying of the skin can be still further facilitated.

Another feature of the invention lies in providing a clamping device which bears a complementary relation to the mold and which is designed to grip the skin from the outside, after the skin has been applied to the mold, so as to facilitate the correct configuration of the finished article. Our invention contemplates the provision of a clamp of this character which will efficiently fulfill the functions which have been heretofore fulfilled by a plurality of ordinary clips and which will in addition have a more efficient effect in determining the final contour of the skin. A preferred embodiment provides this clamp of metallic material so that the heat from the mold will be transmitted to the clamp and thereby enhance its effect.

Heretofore, it has been customary to crumple a mass of paper about the mold, and thereupon apply an adhesive or binder which would subsequently cause the paper to adhere to the inside of the skin and thereby serve as a lining member. This method has been beset with many disadvantages. The proper

crumpling of the paper has necessitated a certain skill, the subsequent application of the binder has necessitated an extra step, an excessive amount of lining material has been necessary, and the finished lining has often been uneven and detrimental to the final quality of the article. It is another object of the invention to provide a method of manufacture which will obviate these disadvantages and which will in addition embody certain other advantages which will effect greater economy and efficiency.

Accordingly, another feature of our invention lies in preforming certain lining members which may be applied over the mold without any particular skill, and which are so constructed as to necessitate no extra step of binder application. Although we have found it quite satisfactory to utilize heavy paper, oil board, or even rubber, nevertheless we prefer to utilize a burlap material for the manufacture of these preformed lining members; and a feature of our invention lies in impregnating the lining member with a binding material which will not only serve to retain the shape of the lining member, but which will subsequently become available for binding purposes. Another feature of our invention lies in utilizing a binder which is capable of softening or otherwise becoming effective upon the application of heat or moisture, whereby the subsequent association with the heated mold and the moistened skin will render the binder effective for its contemplated purpose.

Another feature of our invention lies in constructing the mold of a material which is capable of rapid heating and cooling, whereby not only the speed of manufacture is increased, but whereby the binder will have no opportunity to be dissipated in the moisture of the skin, and the quicker cooling will effect and enhance the correct shrinkage of the skin over the mold.

For the attainment of the foregoing objects and such other objects as may herein-after appear or be pointed out, we have illustrated one embodiment of our invention in the accompanying drawings in which:

Fig. 1 is a perspective view of a mold constructed in accordance with our invention, and attached in a preferred manner to a supporting ledge or table;

Fig. 2 is a perspective view of a clamping device constructed to constitute a com-

plementary element with respect to a mold; Fig. 3 is a side view partly in section, showing the lining member, the skin and the clamping device in relative association with the mold;

Fig. 4 is a perspective view of a lining member, a portion thereof being broken away for the sake of clearness;

Fig. 5 is a top plan of another embodiment 10 of a clamping device; and

Fig. 6 is a section on line 6—6 of Fig. 5.

Referring to the drawings and particularly to Fig. 1 we have shown a mold which comprises a body portion 10, and a snout-shaped end which consists of a medial bridge portion 11, a substantially flat and attenuated base 12, and rear walls 13 shaped to the configuration of the eye-sockets of an animal's head. More particularly, the walls 13 are forwardly concave, and they join and merge with the side walls 14 of the bridge portion 11. The latter slants downwardly from the body portion 10 to the tip of the mold 15, and the base 12 is similarly pointed 23 toward the outer end of the mold so that the base 12 and the walls 14 conform substantially to the shape of the cheeks of an animal's head. Attached to the rear end of the mold is a supporting bracket which comprises an 30 upstanding arm 16, and an offset arm 17 carried at the end of the arm 16 and projecting rearwardly and perpendicularly therefrom. The arm 17 is adapted for attachment to a supporting ledge in such a manner that 35 the mold will project outwardly from the ledge and slightly below it, whereby the mold will be freely accessible from all directions.

We prefer to provide the mold with heating coils 26, and the binding terminals of an electric contact are arranged to project rearwardly from the mold through the arm 16 into the space underlying the arm 17. These terminals 18 are clearly shown in Fig. 45 3, and it will be observed that the arm 17 is sufficiently offset with respect to the mold that the terminals 18 are freely accessible underneath the ledge.

Referring now to Fig. 4, it will be observed that we have shown a lining member which is suitably shaped, preferably of burlap impregnated with a binder, so as to be applicable over the snout-shaped end of the mold. The lining member has a snout-shaped end 19 and a rearwardly projecting body portion 20. The lining member is hollow as may be readily understood, and the impregnated binding material permits it to hold its shape indefinitely.

In Fig. 2 we have illustrated one form of clamping device, and it will be observed that it comprises two juxtaposed jaws 21 with which a spring clamp 22, or equivalent device is adapted to engage. Each jaw 21 is suitably shaped to conform substantially with

one of the cheeks of the mold. Thus, each jaw 21 comprises a substantially flat base 22^a, a rear upstanding wall 23, forwardly concave, and joining and merging with a wall 24 disposed longitudinally of the jaw and slanting downwardly toward the front end thereof. It will be readily understood that when the jaws 21 are applied to the mold, the base 22^a will overlie the base 12 of the mold, and the walls 23 and 24 will conform to the walls 13 and 14. In the embodiment shown, we have illustrated the spring clamp 22 as an inverted U-shaped member extending over the walls 24, and designed to hold the jaws yieldably together. That is, the jaws are spreadable and after they have been applied to the mold, the spring 22 will pinch them to the bridge portion 11.

Referring now to Fig. 3, it will be observed that in carrying out our invention, we first apply the lining member or mask 20 to the mold 10. We then gather one end of the skin to be shaped so as to form a tubular closed end portion which may be moistened and then stretched over the mask 20. We have indicated an illustrative skin so applied by the reference numeral 25. After the skin has been applied, we apply the clamping device shown in Fig. 2, and it will be observed that this device will retain the closed portion of the skin in close conformity with the snout-shaped end of the mold.

It will be readily understood that the application of heat to the mold is entirely optional. The fact that the mold has a surface which will not absorb moisture will in itself permit speedier drying of the skin than would be the case if the mold were made of an absorptive material such as wood. If no heat is applied to the mold, we may utilize a binder in the mask 20 which will become more effective under the application of moisture. In such an event, the application of the moist skin to the mold will of itself render the binding medium effective, and cause the lining member 20 to adhere to the inside of the skin as the latter dries. After the skin is entirely dry, the clamping device is removed, the skin withdrawn, and thereafter it may be suitably finished off by inserting artificial eyes, or by taking any such other steps as may be necessary.

In a preferred method of carrying out our invention, we apply heat to the skin by making a suitable attachment of conducting wires to the binding posts 18. Thus the mold will not only remain unaffected by the moisture, but the applied heat will speed up the drying of the skin, and some of the heat will be transmitted through the skin to the clamping device which will in turn facilitate the drying process. We have found it satisfactory to heat the mold for as short a time as ten minutes. By then removing the conducting wires, we find that the mold cools

very rapidly, and in cooling it causes more effective shrinking of the skin into a conformity with the mold. After ten more minutes have elapsed, we are enabled to 5 move the skin in a perfectly dry and completed condition. In a preferred method of carrying out the invention, the binding material is of a character which will increase its efficiency upon the application of heat, 10 so that the heat of the mold will not only hasten the drying, but will render the binding material operative to secure the lining member within the skin.

It will thus be obvious that we have provided a method and apparatus for achieving the desired results in an extremely quick and efficient manner. We contemplate utilizing approximately thirty molds of a given size, these molds being arranged one next to 20 the other along a ledge of the character shown in Fig. 1. A single operator may quickly apply the mask 30 to a mold, apply the skin and the clamping device, and attach the electric conducting wires. After he has 25 accomplished this much, he may devote his attention to the next mold and repeat the steps at that place. In the course of about ten minutes he can have rendered operative each of the thirty molds, and he is then in 30 a position to return to the first and disconnect the conducting wires. Moreover, the conducting wires may do double duty by serving to heat other molds while certain molds are cooling.

35 Thus, if another set of molds, say of a different size, are arranged along the opposite edge of the ledge, the same worker may apply skins thereto and simultaneously disconnect one of the first set of molds from the 40 electric current and apply the current to one of the second set. After he is through applying the skins to the second set, he may return to the very first mold of the first set and find the skin entirely cooled and dry and 45 ready for removal. The saving in time and labor effected by our invention is clearly obvious.

In Figs. 5 and 6 of the drawing we show a modified embodiment of the clamping means in which these means comprise two elements 31 substantially alike and pivoted together as shown at 32. Each of the elements 31 has its free end bent as shown at 33 so as to permit this member to force 55 the skin into contact with the skull form and is further provided with a downwardly extending portion 34 for this same purpose, from the end of which extends the outwardly extending lug or flange 35. When 60 the clamping members are caused to assume their closed position in connection with the skin and skull mold as shown at Fig. 6, they are held in this position by the wedge slide 36 from the converging outer edges of which 65 extend upwardly the walls 37 and the in-

wardly bent overhanging flanges 38 arranged to engage about the flanges 35. As the wedge slide 36 is moved inwardly, which is done automatically by the spiral spring 40, one end of which 41 is connected with any desired portion of the apparatus, the clamping members 31—31 will not only be forced into clamping association, but will be so held until released, and for these purposes, the slide 36 is provided with a downwardly projecting lug 41 which can be manually engaged and moved against the action of the spring 40 to permit the members 31 to move apart and to be released from the skin and the mold.

Having thus described our invention and illustrated its use, what we claim as new and desire to secure by Letters Patent is:

1. In a mold for shaping animal skins to simulate an animal's head, a body portion comprising a snout-shaped end having recesses defining the eye-sockets, and a clamp comprising juxtaposed jaws which conform in shape to the walls of said recesses.

2. In a mold for shaping animal skins to simulate an animal's head, a body portion comprising a snout-shaped end having recesses defining the eye-sockets, and a clamp comprising juxtaposed jaws which conform in shape to the walls of said recesses, said clamp being provided with resilient means for yieldably holding them in position within said recesses.

3. In a mold for shaping an animal skin to a predetermined contour, a body portion having a suitably configured portion adapted to receive the skin thereover, and a spring clamp removably engageable over said configured portion and conforming in shape thereto.

4. In a mold for shaping an animal skin to the contour of an animal's head, a body portion having a snout-shaped end which comprises a base, a medial wall, and rear transverse walls defining eye-sockets and cheeks, and a complementary spring clamp removably engageable over said end and comprising portions which conform in shape to said eye-sockets.

5. In a mold for shaping an animal skin to the contour of an animal's head, a body portion having a snout-shaped end which comprises a base, a medial wall, and rear transverse walls defining eye-sockets and cheeks, and a complementary spring clamp removably engageable over said end and comprising juxtaposed jaws having configurations which permit them to engage snugly and simultaneously with said base and walls.

6. The combination with a mold having a forwardly projecting snout-shaped portion, of an attaching bracket supporting said mold and carried by the rear end thereof and comprising a rearwardly extending offset portion, electrical heating elements associ-

ated with the mold, and binding terminals therefor extending rearwardly and spaced from the offset portion, whereby the latter may be attached to a table top to render the 5 configured portion and the terminals freely accessible from the front and rear respectively.

7. The method of shaping animal skins to simulate an animal's head, which comprises 10 applying a lining to a snout-shaped mold, coating the lining with a binder whose effectiveness increases with heat, applying the skin to the mold, and heating the mold to cause binding of the lining to the skin.

8. The method of shaping an animal skin to simulate an animal's head, which comprises applying to a snout-shaped mold a lining which is impregnated with a binder whose effectiveness increases with moisture, 20 wetting the skin, and applying the skin to the mold whereby binding of the lining to the skin will be effected.

9. The method of shaping an animal skin to simulate an animal's head, which comprises 25 preshaping a lining to conform with a snout-shaped mold, applying the lining to the mold, coating the lining with a binding material, and applying the skin to the mold to bind the lining within it.

10. The method of shaping an animal skin to simulate an animal's head, which comprises preshaping a lining into the form of a mask conforming to a snout-shaped mold, 30 impregnating the lining with a binder whose effectiveness increases with applied heat, applying the lining and skin successively to the mold, and heating the latter to bind the lining to the skin.

11. The method of shaping an animal skin 40 to simulate an animal's head, which comprises impregnating a flexible lining material with a binder to impart form-retaining stiffness to the material, shaping the latter to form a mask, applying the latter to a mold 45 conforming therewith, applying the skin thereover, and causing the impregnated binder to become effective to bind the mask to the skin.

12. In a method of shaping an animal skin 50 to the shape of an animal's head, the step or steps which comprise preshaping a lining material into the form of head desired, and then applying the latter to a mold conforming therewith.

13. In a method of shaping an animal skin 55 to the shape of an animal's head, the step or steps which comprise impregnating flexible lining material with a binder which imparts form-retaining stiffness to the material, and then shaping the material to form a mask-like lining member.

14. In a method of shaping an animal skin to the shape of an animal's head, the step or steps which comprise impregnating a flexible lining material with a binder which softens under heat and which imparts form-retaining stiffness to the material, shaping the material to form a mask-like lining member, applying said member to a mold, applying the skin thereover, and heating the mold 70 to cause the binder to become effective in binding the member to the skin.

15. In a method of shaping an animal skin to the shape of an animal's head, the step or steps which comprise impregnating a flexible lining material with a binder which softens upon being moistened and which imparts form-retaining stiffness to the material, shaping the material to form a mask-like lining member, wetting the skin, and causing the skin to dry and shrink over said member whereby the moisture will cause binding of the member to the skin.

16. In a method of shaping an animal skin to the shape of an animal's head, the step or 85 steps which comprise impregnating a burlap material with a binder which imparts form-retaining stiffness to the material, and then shaping the material to form a mask-like lining member.

17. For use with an animal skin shaped to simulate an animal's head, a pre-formed mask-like lining member impregnated with a binder which imparts sufficient stiffness to the member to render it self-sustaining.

18. For use with an animal skin shaped to simulate an animal's head, a pre-formed mask-like lining member impregnated with a binder which imparts sufficient stiffness to the member to render it self-sustaining, 100 said binder being softenable whereby the lining member may be secured within the skin by applying the latter thereover and softening the binder.

In witness whereof, we have hereunto 105 signed our names.

BARNEY BILLET.
SAMUEL HEILWEIL.
